SPACER OR CHAIR BAR FOR CONCRETE-REENFORCING BARS.

Application filed May 15, 1925. Serial No. 30,441.

This invention relates generally to improvements in spacers, and particularly to a spacer or chair bar for supporting and spacing steel bars of the type used for reenforcing concrete structures, such as horizontal beams and floor slabs. Prior to this invention, spacers and chairs employed for supporting horizontal reenforcing bars usually included means whereby the reenforcing bar was gripped by the spacer or chair, said means in many cases comprising a tongue, or similar element, formed integral with the spacer or chair, which tongue was bent in such manner that it embraced and thus gripped the reenforcing bar. In the use of spacers or chairs of the type suggested, the operation of bending the tongues so that they would embrace the reenforcing bars was a time-consuming one, and to eliminate this loss of time we have devised the spacer or chair bar disclosed herein, which, briefly stated, comprises a bar formed of more or less resilient material shaped to include one or more gripping elements or chairs. Due to the resiliency of the material of which the bar is formed, and because of the shape of said gripping elements or chairs, the walls of the gripping elements or chairs are capable of frictionally gripping the reenforcing bars so that said reenforcing bars are securely held without the use of the tongues or similar elements formerly employed.

The main object of the present invention therefore is to produce an extremely simple and inexpensive spacer or chair bar which is so constructed that the elements which are adapted to engage the reenforcing bars will frictionally grip said reenforcing bars, thus providing for secure connection between the spacer or chair bars and the reenforcing bars, and without the use of the external gripping elements formerly used.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a fragmentary perspective showing fragments of a plurality of spacer or chair bars and fragments of reenforcing bars

associated therewith, and showing the manner in which the reenforcing bars are supported and spaced by our improved spacer or chair bars.

Fig. II is a section on line II-II of Fig. I.

Fig. III is a plan view of the fragments of the spacer or chair bar and the reenforcing bar shown in Fig. II.

In the drawing, A designates our improved spacer or chair bars which are preferably made of metal of a more or less resilient nature. Specifically stated, each of the spacer or chair bars comprises an elongated bar shaped so as to be provided with a plurality of gripping elements or chairs B, which are spaced apart from each other in a direction parallel with the length of the bar. Each of the gripping elements or chairs B is preferably formed integral with the bar of which it forms a part, said gripping elements or chairs comprising oppositely disposed portions 1 which extend upwardly from the main portion 2 of the bar and inner gripping portions 3 located between the oppositely disposed portions 1. The lower end portions of the inner gripping portions 3 of the chairs B are in the form of loops, and each of said inner portions extends some distance downwardly below the main portion 2 of the bar (Fig. II).

4 designates a curved seat which forms a part of the inner gripping portion of each chair B, said seats being each formed by a pair of oppositely disposed walls shaped to correspond approximately with the cross sectional shape of the reenforcing bars C, and said seats being adapted to receive the reenforcing bars C, as suggested by Fig. II. It will be noted that the seats 4 are open at the top to provide a space 5 which permits the reenforcing bars C to be introduced into said seats, but as will be observed, said spaces 5 are not as wide as the diameter of the reenforcing bars. Because of this arrangement it is apparent that to introduce the reenforcing bars C into the seats 4 the upper portion of the gripping elements or chairs B must be spread apart, as suggested by dotted lines in Fig. II. 6 designates curved portions at the top of gripping elements or chairs B at the points where the upwardly extended portions 1 join the inner gripping portions 3. In supporting and spacing reenforcing bars within a form by means of our improved spacer or chair bars,

said spacer or chair bars are first located within the form, said bars being supported in any suitable manner and being spaced the proper distance apart. When the bars have 5 been properly positioned, the gripping elements or chairs B are arranged in rows so that the axes of the seats are in alinement. This arrangement will cause the spaces 5 above the seats to be in alinement also, as 10 shown in Fig. I. The elongated reenforcing bars C are then arranged so that each bar C is supported by the upper portions of a row of gripping elements or chairs B. When the bars are arranged as described, 15 said bars are positioned as suggested by dotted lines in Fig. II; that is, with said bars resting upon the upper curved portions 6 of the chairs and with the lower portions of said bars extended into the spaces 5. The 20 bars C are then depressed in any suitable manner, for instance, by the operator stepping upon them, and said bars are forced downwardly. This will cause the upwardly extended portions of the chairs to be 25 spread apart until said bars have been forced into the seats 4, when the oppositely disposed walls of the chairs will move toward each other and frictionally grip the bars C.

We have shown reenforcing bars in the 30 drawing which are round in cross section, but it is apparent that reenforcing bars of any other cross sectional shape may be employed, and also it is plain that the shape of the gripping elements or chairs may be 35 changed without departing from the spirit of our invention.

When our improved spacers or chair bars are in use in a form, the lower looped portions of the inner gripping portions of the chairs function as legs for supporting said 40 bars, consequently said bars are adequately supported when the reenforcing bars C are forced downwardly to move said reenforcing bars into seats 4.

We claim:

A device for supporting and spacing elongated reenforcing bars for concrete structures, comprising a flat narrow brace having integrally formed portions thereon for gripping the reenforcing bars, said brace being formed of resilient material, and said gripping portions being located at spaced intervals along the lengthwise dimension of said brace, each of said gripping portions being provided with a U-shaped bottom having the upper walls thereof flared outwardly in a shape corresponding approximately to the cross-sectional shape of the reenforcing bars, the lengths of said brace between successive gripping portions being countersunk to provide vertically extending walls adjacent to each side of the flared walls of said gripping portions whereby the braces serve not only to support and to space the reenforcing bars, but also as means to reinforce the concrete structure in a direction at right angles to the lengthwise dimension of the reenforcing bars.

In testimony that we claim the foregoing we hereunto affix our signatures.

CLARK P. SCHUMACHER.
LEON B. SCHUMACHER.
